UNITED STATES PATENT OFFICE.

MELVILLE CLARK, OF CHICAGO, ILLINOIS.

DUPLEX TRACKER-BOARD FOR AUTOMATIC MUSICAL INSTRUMENTS.

No. 884,366.

Specification of Letters Patent.

Patented April 14, 1908.

Application filed February 14, 1907. Serial No. 357,318.

REISSUED

To all whom it may concern:

Be it known that I, MELVILLE CLARK, a citizen of the United States, residing at Chicago, in the county of Cook and State of Illinois, have invented new and useful Improvements in Duplex Tracker-Boards for Automatic Musical Instruments or Players, of which the following is a specification, reference being had to the drawings forming a part thereof.

The purpose of this invention is to provide a tracker board construction for automatic musical instruments or players by which such instruments may be adapted to employ controlling sheets having their perforations cut according to different scales,—that is, spaced more or less widely from center to center of the perforations.

It consists in the construction described and illustrated and indicated by the claims.

In the drawings: Figure 1 is a fore-and-aft vertical section through a duplex tracker board and adjusting parts of an automatic musical instrument embodying my invention in one of its forms. Fig. 2 is a partly sectional plan view of the two tracker boards, section being made at the planes of the ducts in the two boards respectively. Fig. 3 is an edge view or front elevation of the structure shown in Fig. 1. Fig. 4 is a view similar to Fig. 1 showing a modified construction for the same purpose. Fig. 5 is a section at the line 5—5 on Fig. 4. Figs. 6, 7, 8, 9, 10, 11 and 12 are sectional views similar to Fig. 4 showing each a different modification for the same general purpose. Fig. 13 is a detail front edge elevation of a portion of the form shown in Fig. 7.

In the construction shown in Figs. 1, 2, 3 and 4 the tracker board, 1, has the mouths of the ducts, *a*, spaced according to a different scale from the tracker-board, 2. The first may be understood as indicating, for example, spacing of one-sixth of an inch,—that is, having the distance between centers of consecutive duct mouths one-sixth of an inch,—and duct-board No. 2 may be understood as having the duct-mouths spaced say one-tenth of an inch between centers. In the two tracker-boards, at a distance back from the edge having the duct-mouths, the ducts, *3*, are equally spaced and at this point both duct-boards are provided with ports, *4*, leading to the surface from the several ducts.

One of the duct-boards, preferably the longer one, 1, may be mounted fixed in position with respect to the supporting frame structure, and the other mounted behind it along the path of travel of the controlling sheet, 5, is mounted directly upon the first, with capacity for movement from position at which the ports of the two boards register, to a position at which the ports of both boards are closed, each by contact with the other board. In order to insure such closing, the proximate and contacting faces of the two boards, for a distance each way from the ports, may be provided with a felt strip, 6, which affords the port-closing surface.

The tubes, 7, which lead to the pneumatic action (not represented) are connected, preferably, to the ducts of the fixed board, 1; and this board is provided with means for closing its duct-mouths when its ports, 4, are registered with the ports, 4, of the other board. Such registration occurs when the board, 2, is adjusted to protrude beyond the board, 1, so as to receive the contact of the controller sheet. The device for covering the duct-mouths may be a lip, 8, pivoted by means of bracket ears, 8^a, at the ends of the tracker board, 1, and adapted to be swung down forward of said board to uncover the ducts and to be swung up over the edge of the board to cover them, the brackets being slotted at their pivotal connections, and a spring being provided at each end for holding the lip snugly against the edge of the tracker board when the lip is in duct-closing position. The springs will be adapted to yield to accommodate the movement of the lip in swinging off the edge of the board and around the lower corner to position where it is out of the way of the controller sheet.

An automatically operated device for closing the duct-mouths of the board, 1, is shown in Fig. 6 consisting of a lip, 10, lodged in a rabbet, 2^a, on the side of the board, 2, which faces the board, 1, said lip being pivoted to the board, 2, and adapted to swing over onto the edge of the board, 1, closing its ducts when the board, 2, is protruded to take the contact of the controller sheet. A spring, 11, may be provided for holding the lip thus over in position to close the duct-mouths of the board, 1. When the board, 2, is retracted, the lip, 10, rocks over the edge of the board, 1, back into position occupying the

rabbet, 2^a, of the board, 2, and is withdrawn with said board, 2, down alongside of the board, 1, leaving the edge of the latter protruded to receive the contact of the paper. 5 This construction requires the protrusion of the board, 2, for taking the contact of the paper by the amount of the width of the lip, 10. The form first above described, in which the lip for closing the duct-mouths of the board, 1, is not automatically operated, 10 does not require so much greater protrusion of the board, 2, and may in some cases be preferred for that reason although it is not automatic. 15 In Figs. 7 and 13 there is shown a further modification in which the two tracker boards are both movable edgewise to bring one or the other at will into operative relation with the perforated controller sheet, 5, said 20 tracker boards being retained between guides, 41, on the end cheeks of the case, and stopped by pins, 42, encountering such guides at the limits of the adjustment of the boards in each direction. For closing which-ever board is out of service there is provided an angle bar, 43, mounted for rocking over an axis lying in the plane of contact of the two boards with each other and parallel with their edges in such position that one 25 face of the angle bar seats upon the edge of one tracker board when the other tracker board is protruded so as to stand alongside the outer edge of the angle bar, said angle bar being thus located precisely similarly 30 with respect to the two tracker boards and so that which ever board is protruded to take the contact of the controller sheet will hold one of the lips of the angle bar in position closing the mouth of the ducts of the other board. The remote edge corners of the 35 tracker bars are beveled and both wings of the angle bar have at the outer edge a protruding beveled lip, 43^a, which fits the beveled corner of the tracker board when the 40 lip of the angle bar is situated on the latter for closing its ducts, and the coöperation of the inner edge of the tracker board which is protruded with the beveled lip, 43^a, of the angle bar when the tracker board is thus 45 protruded to the limit operates to crowd the other wing of the angle bar down on to the edge of the tracker board for securely closing the ducts of the latter, thus dispensing with any spring or other expedient of such nature 50 for that purpose.

In Fig. 8 there is shown another form of the application of this invention, in which the two trackers are both fixed in position. In this figure the invention is shown applied 55 to trackers consisting of metallic mouth-pieces having nipples for attaching the flexible tubes leading to the pneumatic action. In applying the present invention to trackers of this type, I construct a tracker duct bar, 20, having the two sets of mouths, 20^a, 20^b,

spaced according to different scales, the ducts from the mouths leading through nipples, 21^a and 21^b, which are connected by the flexible tubes, 21, merging in the tube, 22, running to the pneumatic action. Both sets of mouths, 20^a and 20^b, are thus at all times connected with the pneumatic action. For cutting off either set and leaving the other operative, I provide a tracker-mouth plate, 24, which seats on the tracker duct bar, being of suitable width to cover both sets of mouths with a margin at each side. This cap has two sets of apertures, 24^a and 24^b, corresponding in spacing to the two sets of duct mouths, 20^a and 20^b, of the tracker duct bar. These two rows of apertures, 24^a and 24^b, are spaced apart such distance that when the set, 24^a, for example, registers with the tracker duct mouths, 20^a, the other set, 24^b, is out of registration with the corresponding set of tracker duct mouths, 20^b; and when the tracker mouth plate is moved laterally to register the apertures, 24^b, with the duct mouths, 20^b, the duct mouths, 20^a, are closed by an unperforated portion of the plate. 70 This plate is conveniently mounted for movement to register either set of its apertures with the corresponding set of tracker duct mouths, by means of bracket end pieces, 25, 25, extending past the ends of the tracker duct bar, 20, and pivoted thereto for rocking in the direction of travel of the controller sheet a sufficient distance to shift the registration of its two sets of apertures as described. Stops, 26, 26, are provided against 75 which the bracket end pieces, 25, are stopped to limit the movement in each direction at the proper point for registration of the apertures with the ducts, as described; and any convenient operating device may be provided for rocking the plate, as the rock shaft, 27, mounted on the tracker board and having lever arms, 28, 28, connected to the brackets, 25, by short links, 29, insuring substantially equal rocking movement at the two 80 ends but preventing distortion of the device in operation. It will be understood that the controller runs at all times upon the outer surface of the plate, 24, whose apertures become in effect the tracker mouths. It is immaterial which of the two elements, 20 or 24, which together constitute the complete tracker bar or board is the movable element. 85

The wooden equivalent of the metal construction above described is shown in Fig. 9, in which the tracker duct board, 24^x, has for connection with the tubes, 22, a single set of ducts, 21^x, which are branched to two sets whose mouths, 20^a and 20^b, at the upper edge are differently spaced to correspond to the two sets of mouths, 24^a and 24^b, of the duct board mouth piece, 24^x.

In the form shown in Fig. 10, the tracker bar, 20^y, has the two sets of tracker mouths 20^a and 20^b, differently spaced as in the 130

other forms, the ducts from the mouths of the closer spaced set, 20^a, diverging, and those from the wider spaced set, 20^b, converging, so that at the back or inner edge of this tracker duct bar the ducts of two sets are equally spaced. The base or inner element, 24^y of the tracker board of this form has the single set of ducts, 21^y, to which tubes, 22, are connected, branched to two sets of branches, 21^w and 21^z, for registration respectively with the equally spaced inner ends of the two sets of ducts leading from the differently spaced mouths, 20^a and 20^b, of the outer elements, 20^y, but these two parallel sets of branched ducts are separated from each other a distance differing from the distance apart of the two sets of ducts in the element, 24^y, so that the two elements being moved relatively the amount of this difference the registration between the ducts of the upper element and the branched ducts of the lower element may be shifted to establish operative communication with either set of mouths, 20^a or 20^b, at will.

In Fig. 11 the rear or inner element of the tracker board has only a single set of ducts which is adapted to be registered with the inner ends of either set of ducts leading from the mouths, 20^a and 20^b, of the forward or outer element of the board, the registration being shifted by relative movement of the two elements, as in the other forms.

In the modification shown in Figs. 4 and 5, the two tracker-boards, 1 and 2, are mounted fixedly in position at which the controlling sheet, 5, passes over and rests upon both edges in its travel, so that said sheet may co-operate with either one of said tracker-boards which has its ducts open for connection with the pneumatic action. In these tracker-boards the ducts are spaced at their mouths according to different gages, as already described. The two boards, although mounted close together at their edges over which the controlling sheet travels, diverge from said edges, and at a distance back from their said edges, several inches apart, each board is provided with ports, 4, leading from their proximate faces into the respective ducts, and a duct-board, 16, is interposed between the two divergent tracker-boards, making a third side of the triangular structure. The ducts, 16^a, in this duct board diverge from one edge toward the other, being at one side spaced for registration with the ports, 4, of the shorter tracker-board, 2, and at the other edge spaced for registration with the ports, 4, of the longer tracker-board 1. The tubes, 7, leading to the pneumatic action are connected to the ducts, 16^a, of the duct-board, 16, at any convenient point intermediate the two lateral edges of said duct-boards, and said board is movable longitudinally with respect to the two tracker-boards a distance slightly

more than the diameter of the ports, 4, with which the mouths of the ducts, 16^a, are adapted to register. Said ducts, however, are so located in said board that they will not register at their opposite ends at the same time with the ports of the two tracker boards, but when said ducts register at one edge with the ports, 4, of one tracker-board they are out of registration with the corresponding ports of the other board, which are closed by the edge of the duct-board, 16. Either tracker-board may therefore be brought into operative connection with the pneumatic action by adjusting the duct-board, 16, one way or the other for registration of its ducts at one end or the other with the tracker board against which it bears at that end. The duct-board, 16, is mounted and maintained in proper relation to the two tracker-boards by being retained between guide strips, 17, on said boards respectively; and stops, 18, 18, at opposite ends limit its adjustment in one direction or the other for registration with one board or the other; and it may be moved by hand to either position, a suitable handle, 19, being provided for such purpose.

In Fig. 12 there is shown the application of this invention to a tracker which consists of a metallic mouth-piece having nipples for attaching the flexible tubes leading to the pneumatic action. For applying this invention to a construction of this sort I preferably construct the metallic tracker, 20^d, with two differently spaced sets of ducts leading to two sets of nipples, 21^a and 21^b, and back of or below such metallic tracker mouth-piece I mount in a fixed support pipe Y's, 40, the flexible tubes, 22, being connected to the stems of the Y's and leading to the pneumatic action, and a flexible tube, 22^b, extending from one branch of each Y to a nipple, 21^a, of the longer tracker mouth-piece, a similar flexible tube, 22^c, extending from the other branch of the Y to the corresponding nipple, 21^b, of the other tracker mouth-piece. The metallic tracker, 20^d, with its nipples, 21^a and 21^b, is mounted by means of bracket end pieces, 35, for rocking about a pivot some distance back of the face of the tracker over which the paper travels, and at opposite sides of the position at which either set of duct-mouths stand for co-operation with the controlling sheet there are provided two fixed valves or covers, 30 and 31. When the tracker 20^d is rocked to bring the longer set of duct-mouths into co-operative relation to the controllers, the other series is under the valve or cover, 31; and when the shorter series is in position for co-operating with the controller the longer series is under the cover, 30, so that only one of said series of duct-mouths is open at operative position at any time. The lever handle, 33, attached to the rock-shaft, 34, on which the metallic

tracker, 20^d, is mounted by means of its bracket-arms 35, serves to rock the tracker to one position or the other as desired.

I claim:—

- 5 1. In an automatic musical instrument or player, in combination with a traveling controller, a tracker device having a plurality of sets of duct mouths differently spaced, the ducts of the closer spaced set being diverged from the mouths, and those of the wider spaced set being converged from the mouths; an element having ducts and flexible tubes connected therewith, the ducts in said element being adapted to register at one position with the said converged ducts and at another position with the diverged ducts of the tracker, and means for relatively adjusting said element and the tracker to effect either registration at will.
- 10 2. In an automatic musical instrument or player, in combination with a traveling controller, a tracker device consisting of two elements, one element having two sets of duct mouths and the other element having a single set of ducts branched to two sets of duct terminals corresponding to the ducts from the two sets of duct mouths of the first element, said sets of duct mouths and duct terminals being relatively disposed on said two elements so that only one set of terminals can register at a time with the ducts from the corresponding set of mouths, and means for relative movement of said two elements to shift the registration at will from one set to the other.
- 15 3. In an automatic musical instrument or player, in combination with a pneumatic action a traveling controller, a tracker device having two sets of duct mouths differently spaced; ducts extending from said two sets to a plane at which they are equally

spaced, the element in which the ducts are contained being terminated at such plane; a second element of the tracker having ducts which terminate similarly spaced at the same plane, and adapted to be adjusted for registration of its duct mouths at will with the duct mouths of either set of ducts of the first element and a single set of tubes leading from the ducts of said second element to the pneumatic action.

4. In an automatic musical instrument or player, in combination with a pneumatic action a traveling controller, a tracker device comprising an outer or forward element having at the edge on which the controller travels two sets of duct mouths differently spaced, said ducts leading from said mouths through said element, and a second element having ducts extending therethrough constituting a single set at one side, and connections therefrom at that side to the pneumatic action, said ducts being branched toward the other side to form two sets of terminals spaced respectively to correspond with the spacing at the inner side of the two sets of ducts of the outer tracker element, said two sets of terminals being separated from each other a distance different from that which separates the two sets of ducts of the said outer element, said two elements of the tracker being relatively movable to register at will either set of ducts of one element with the corresponding set of the other element.

In testimony whereof, I have hereunto set my hand, in the presence of two witnesses, at Chicago, Illinois, this 26th day of January, 1907.

MELVILLE CLARK.

In presence of—

EDWARD T. WRAY,
CHAS. S. BURTON.
